UNITED STATES PATENT OFFICE.

CHARLES H. AYARS, OF SALEM, NEW JERSEY, ASSIGNOR TO AYARS MACHINE COMPANY, OF SALEM, NEW JERSEY, A CORPORATION OF NEW JERSEY.

CAN-TESTING MACHINE.

SPECIFICATION forming part of Letters Patent No. 778,622, dated December 27, 1904.

Application filed August 10, 1903. Serial No. 168,971.

To all whom it may concern:

Be it known that I, CHARLES H. AYARS, a citizen of the United States, residing at Salem, in the county of Salem and State of New Jersey, have invented certain new and useful Improvements in Can-Testing Machines, of which the following is a specification.

This invention relates to machines for testing sheet-metal cans, and is particularly an improvement on that class of testing-machines in which the cans are first filled with compressed air and while so filled submerged in a liquid and the leaks in the can detected by bubbles caused by the escaping air through the defective portion of the seam or joint and rising in the liquid.

The invention consists in the combinations and arrangement of devices hereinafter described, and more particularly pointed out in the appended claims, reference being had to the accompanying drawings, in which—

Figure 1 illustrates a central vertical sectional view of a machine embodying my invention. Fig. 2 is a side elevation of same with the tank illustrated in section. Fig. 3 is an enlarged sectional detail view of the clamping-head and adjoining mechanism; Fig. 4, an enlarged detail of the plunger-operating mechanism, and Fig. 5 a detail perspective view of the tongue for feeding the can-bodies to be tested.

Referring to the drawings by letters, A designates a tank or receptacle of any suitable construction to contain liquid, such as water. A rectangular frame B is supported horizontally above the tank by means of suitable legs b, which rest on the bottom of said tank. At opposite sides this frame is provided with bearings C, which support a hollow shaft C', on one end of which latter is a bevel-gear C², which meshes with and is driven by a pinion C³. The shaft C' is also provided with a distributing-chamber e, from which a plurality of pipes or tubes c' project and extend in the present instance in a direction parallel with the said shaft C', as clearly illustrated in Fig. 1, and for a purpose to be hereinafter described. A circular plate or table D is mount-

ed on said shaft C' and is adapted to be revolved in a vertical plane, so that the circumference of said plate or table will travel through the tank or receptacle.

A plurality of brackets E are secured to what I term the "front side" of the plate or table D, preferably near the rim edge or circumference thereof, and these brackets are each substantially U-shaped in side elevation and are each provided near their point of connection with the table with horizontally-extending bearings e, through each of which extends a plunger or stem e'. These plungers e' are each provided on one end with a disk or head e², which latter move with the plungers in a horizontal direction, but are secured against lateral or circular movement by means of two lugs e³, which take on opposite sides of a web e⁴ on the brackets. Each of these disks or heads e² is also provided with a port e⁵, which extends from their outer circumferential edges to the center, as clearly seen in Fig. 3. A pipe f is tapped into the circumferential edge of each of these heads and is in communication with the passage or port e⁵, and each of said pipes is provided with a valve f', having an operating-blade f². A flexible tube f³ connects each of said pipes f with one of the tubes c projecting from the distributing-chamber c. It will thus be seen that communication is established between the air-distributing chamber c and each of the disks or heads e² by means of the ports e⁵, pipes f, flexible tubes f³, and tubes or pipes c'.

Secured to the frame B and projecting inwardly toward the plate D are two arms e² and e³, which latter have a position in the circular travel or path of the valve-blades f² and are designed to shift or turn said blades, so as to first open and then close the valves f'. This operation takes place after the can-bodies have been clamped in position for testing.

The disks or heads, as has been heretofore stated, have a horizontal movement with the plungers or stems e'. This movement is provided for the reason that the said heads are to serve as a clamping-head to hold a sheet-metal body during the testing operation. The

mechanism for accomplishing this horizontal movement will, therefore, now be described

Secured to the rear surface of the table or plate D and directly opposite each of the 5 brackets E is a housing or box g, which is provided with parallel side walls g', having longitudinal slots g''. A shaft g' extends cross-wise of said housing and at right angles to said side walls g' and at each end is provided 10 with a roller g'', which fits into said slots and are adapted to roll therein, as clearly shown in Fig. 3. A bell-crank-shaped lever h is mounted on the shaft g' between said walls g', and said lever is provided with arms h' and 15 h'', the former projecting outwardly from said housing and carrying a roller h'' on its outer end and the other arm, h'', projecting downwardly in an inclined direction and at its lower end being pivotally connected to the end of 20 the stem or plunger e'. A lug h'', also provided on the side of the lever h, serves as a convenient device by which to secure one end of a spiral spring i. The other end of said spiral spring is attached to an arm i', carried 25 on the table or plate D. This spring serves to keep the bell-crank lever h in the position shown in full lines in Fig. 4, and thus keep the plunger e' and head e'' normally pulled outwardly toward the plate or table D and in 30 the position ready to receive a can-body.

Suitably supported within the tank or receptacle A and at the rear of the table D is a segment-trackway j, which latter has position in a vertical plane and partly surrounds the shaft C'. The position of this trackway with 35 respect to the housings g is such that the roller h'' on the arm h' will contact with the said trackway and drag or trail behind the housing g as the latter is moved in a circular path 40 with the said table D. This trailing position of the arm h' is clearly illustrated in full lines in Fig. 2 and by broken lines in Fig. 4. As the arm h' is thus shifted from a position at 45 right angles to the table to an inclined position with respect to said table the integral arm h'' will move toward the table and assume an almost vertical position. This movement of said arm h'' will push the plunger e' and head attached thereto outwardly, as shown in 50 the lower portion of Fig. 2. As the table continues to revolve the rollers h'' will be freed from contact with the segment-trackway j, and the arms h' and h'' will be drawn by the 55 spring i to their normal or released position. The brackets E have been described as being substantially U-shaped in side elevation, and up to the present time only one end of these brackets has been described. The outer ends will therefore now be described, reference 60 being had to Figs. 1 and 2. The extreme outer end of each of these brackets is provided with a circular head k, through which a threaded bolt k' passes, and on each side of said head k', these bolts are provided with a lock-nut k'', 65 by means of which the bolts may be adjust-

ably secured. The inner ends of each of these bolts carry a plate k'', which has position in a vertical plane and may be adjusted or moved in a direction lengthwise of the bracket E by simply adjusting the bolt k'. This adjustment 70 is provided in order that the distance between the said plate k'' and the head e'' may be varied according to the length of the can to be tested. These plates k'' have position directly in front of the heads e'', and the bodies to be tested are 75 to be clamped between said heads and plates with the bottom of the can l seated against the plate. At the head or disk end of the bracket is secured another plate l', which is formed so as to partly surround the said head, 80 and this plate l', together with the plate k'', form guides between which the can-body l passes to get into its correct clamping position in front of the head e''. The brackets are also 85 provided with can-supporting track-rails, one end l'' of which is secured to one bracket and extends in a tangential direction, as at l'', with respect to the circumferential edge of the table and then turns and extends in a direction at right angles, as at l'', and passes down between the guide-plates k'' and l'' of the next 90 preceding bracket and forms a can-body loop or pocket m between said plates and in front of the head e''. These track-rails serve two purposes—first, to receive and hold the can-body in the loop m previous to its being clamped, and, second, to serve as rails for the can-bodies to roll over to be discharged onto a chute m', as will presently be more fully described. 95

At one side of the tank and secured to the frame B is a vertical support n, which pivotally carries a tongue n' and also serves to support the lower end of a can-chute o. This tongue at one end is provided with a curved seat n'', which adjoins the lower end of the chute and is adapted to receive one can at a time, and the opposite end n''' of said tongue projects over the tank and has position in the path of travel of the several brackets E. The seat end n'' of the tongue is heavier than the end n''' in order that said latter end will be raised, as shown in full lines in Fig. 2, when not in contact with either of the brackets. 100

As the plate or table D is revolved the brackets E will successively contact with the end n''' of the pivoted tongue n' and press said end downwardly and raise the opposite end n''. This operation raises the can-body, and as the bracket E reaches or registers with the end 110 of the chute o the can-body will roll off the curved seat n'', because of the inclination of same, and fall between the guide-plates k'' and l'' and drop into the pocket m, formed by the rails. The table and brackets continue 115 to revolve until the tongue is freed, whereupon the same will automatically return to the normal position by reason of the fact that the end n'' is heavier than the end n', and another can-body will be seated in the curved 120 seat n''. The table and brackets continue 125 to revolve until the tongue is freed, whereupon the same will automatically return to the normal position by reason of the fact that the end n'' is heavier than the end n', and another can-body will be seated in the curved 130

seat n^2 . As the table or plate and the brackets continue to revolve or move in their circular path the bodies are clamped, the valves operated to turn on the air, and the can-body submerged and tested, as will be readily understood. After the cans have been moved through the liquid and tested they are elevated until the bell-crank lever h is released by reason of the roller h^3 disengaging the segment-trackway j , whereupon the plunger e and head c^2 will be drawn away from the can-body l , and the latter will then roll down the tangential portion l^3 of the track-rails and onto a chute m' . If the can-body has been found to leak, as would be noted by the escape of bubbles when submerged, the body is removed from the chute m' and properly soldered, while the perfect bodies are permitted to roll down said chute to any desirable point.

20 Air may be supplied to the chamber c through the hollow shaft C' from any suitable source of supply.

Having thus fully described my invention, what I claim as new, and desire to secure by Letters Patent, is—

1. In a can-testing machine the combination with a liquid-tank, of a rotary carrier; a plurality of brackets on said carrier; can-body clamps sustained by each bracket; track-rails having their opposite ends secured to adjacent brackets and between their secured ends having a pocket; means for depositing cans to be tested in said track-rail pockets; means for operating the clamps; a stationary can-receiving chute with which the track-rails register as they move with the brackets, and means for successively releasing the clamps to discharge the tested cans while the track-rails and stationary chute are in register.

2. In a can-testing machine the combination with a liquid-tank, of a rotary carrier; brackets on said carrier; can-body clamps for each bracket; track-rails secured stationarily to each bracket and having a loop forming a pocket between a pair of clamps, said rails extending laterally from said pockets; means for operating the clamps; a stationary chute with which the laterally-extending portions of the rails register while in an inclined position and means for releasing the cans to permit them to roll down the inclined rails into the stationary chute.

3. In a can-testing machine, the combination with a tank to contain liquid; a rotary carrier; a plurality of brackets mounted on said carrier and adapted to be passed through said tank; a housing also mounted on said carrier near each of said brackets and each housing having a slot in its side walls; a shaft extending through said housing and supported in said slots; a lever mounted on said shaft and provided with a projecting operating-arm; a trackway with which said arm engages, and a plunger movable through each of said brackets

ets and carrying a clamping-head on one end 65 and the other end of said plunger being connected with said lever.

4. In a can-testing machine the combination with a liquid-tank, of a rotary carrier; a bracket secured to the carrier and projecting 70 at one side thereof; a housing also secured to said carrier and projecting at the opposite side from the bracket; a plunger extending through said bracket and carrying a clamping-head at one end and having its other end terminating in the housing; a bell-crank lever mounted in said housing and having one end connected to said plunger end and its other end projecting laterally from the housing; a stationary device for rocking the bell-crank 80 lever and holding it in its rocked position while the housing is passing through the liquid, and means for supplying air to the cans while the bell-crank lever is held in its rocked position.

5. In a can-testing machine the combination with a tank; a rotary carrier; a plurality of brackets mounted on said carrier; a can-body-clamp device carried by each of said brackets; a trackway supported between each two 90 adjoining brackets and movable with said carrier and along which the can-bodies roll after being released by the clamp device, and means whereby air may be supplied to the interior of the bodies while held by said clamping 95 devices.

6. In a can-testing machine the combination with a tank; a shaft; an air-distributing chamber revoluble with said shaft; a carrier; a plurality of brackets mounted on said carrier; a plunger movable through each of said brackets and carrying a clamp-head which latter are each provided with an air-passage; a pipe connecting each clamp-head with the revoluble air-chamber and at all times in communication with the latter and each of said pipes having a valve; means for successively opening the valves and permitting air to pass to each head as the latter enters the tank, and means for successively closing each valve as 105 the heads pass out of the tank.

7. In a can-testing machine, the combination with a tank; a rotary carrier; a plurality of brackets mounted on and moving with said carrier; can-body-clamping devices carried by 115 said brackets; a can-body support for each of said brackets; a chute; a tongue pivoted near the end of said chute and having a seat for a can, and projecting over said tank and in the path of said brackets whereby each bracket 120 will operate said tongue to successively feed a can.

In testimony whereof I affix my signature in the presence of two witnesses.

CHARLES H. AYARS.
